UNITED STATES PATENT OFFICE.

HERBERT E. ENSLIN, OF MALDEN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

METHOD OF AND MACHINE FOR MARKING SHOE-UPPERS.

1,313,943.

Specification of Letters Patent. Patented Aug. 26, 1919.

Application filed December 28, 1915. Serial No. 68,994.

To all whom it may concern:

Be it known that I, HERBERT E. ENSLIN, a citizen of the United States, residing at Malden, in the county of Middlesex and

5 State of Massachusetts, have invented certain Improvements in Methods of and Machines for Marking Shoe-Uppers, of which the following description, in connection with the accompanying drawings, is a 10 specification, like reference characters on the drawings indicating like parts in the several figures.

The present invention relates to the art of marking shoe uppers and is more especially 15 directed to improved methods and mechanisms for marking shoe uppers for buttons and buttonholes.

It has been proposed to mark the locations 20 of the buttons and buttonholes on the quarters and flies before the parts of the upper are finished and stitched together. In this method of manufacture, it is possible that the button and buttonhole locations may not align when the fly and quarters are stitched 25 together and overlapped, because of inaccuracy in the lines of junction of the parts.

It has also been proposed to mark the fly 30 for buttonholes by a hand marking implement operating through a pattern plate or stencil, to cut and finish the buttonhole and stitch the fly and quarters together, then to fold the upper with the quarter and fly properly overlapped and to mark the button 35 locations on the button quarter in line with the eye ends of the buttonholes by a hand tool inserted through the buttonholes in the superposed buttonhole fly. This hand operation, however, is slow and has the added 40 disadvantage of failing to allow for the tipping or overlay of the buttons due to the play of the button eye in its fastening. Such an allowance should be made in marking so that when the shoe is buttoned, the edge of the button quarter will be maintained exactly beneath the center seam which constitutes the line of crimping or folding of the 45 upper.

In one of its aspects, the invention comprises a method of marking button locations 50 which is characterized by uniting the fly and quarters of the upper, folding them in properly overlapped relation, utilizing the ends of the buttonhole locations on the overlying fly as guides and marking the under-

lying button quarter at points spaced lengthwise from said ends to indicate the points for the subsequent attachment of the buttons.

In a related aspect, the invention includes a method of marking button locations on the quarter of a folded united upper in which the buttonholes have been formed which is characterized by the marking of the button locations on the button quarter at points offset from the eye ends of the corresponding buttonholes in the overlying fly in the direction of length of the buttonholes and which, as practised by the illustrated machine, consists in positioning a marking element between the fly and quarter in line with and offset from the buttonhole location, as described, and operating upon the fly to actuate the marking medium. Conveniently, when the buttonholes have been previously formed in the fly the marking medium may be operated through the buttonhole in the overlying fly.

The invention also includes within its scope novel mechanism with the aid of which these novel methods may be carried out in a convenient manner, although the machine may be used in the practice of other methods than those herein disclosed, while the methods described may be carried out by the use of machines or apparatus of many different types as will be apparent to those skilled in the art.

One feature of the machine consists in intermittently and automatically operated buttonhole location marking means, with means for feeding the stock to said marking means intermittently and alternately with the marking operations.

Another feature of the invention resides in mechanism constructed and arranged to mark on the folded upper the locations of buttons and buttonholes substantially simultaneously and for a number of successive buttons and buttonholes, including intermittently and automatically operated means to mark the button and buttonhole locations, with means for automatically feeding the folded upper to the marking means, intermittently and alternately with the marking operations.

A further feature of the invention consists in certain mechanism for marking the fly and button quarter of a folded upper

substantially simultaneously and at relatively offset points to indicate the buttonhole and button locations, and with means for supporting the folded upper in marking position.

Additionally, a feature of the invention consists in mechanism for marking button and buttonhole locations on a folded shoe upper substantially simultaneously including button and buttonhole marking instrumentalities coöperating with work gaging and guiding means and constructed and arranged for one adjustment to mark buttonhole locations on a separate fly, and for further adjustment to mark button locations on the button quarter of the folded upper having the same fly attached with the buttonholes formed therein.

So far as I am aware the machine of my invention is the first machine devised and constructed to mark button or buttonhole locations, or both, having intermittently and automatically operated marking means, with means for automatically feeding the stock to the marking means intermittently and alternately with the marking operations.

Another feature of the invention consists in the combination with power operated instrumentalities for intermittently operating on the work to mark the work and for intermittently and alternately feeding the work to the marking instrumentality, of controlling mechanism arranged to stop the operation of said instrumentalities at the end of a selectively predetermined number of successive operations. From this viewpoint, the "marking" or locating feature of the invention may have a wide range of equivalents and may include marking by perforation or cutting as well as marking by imprinting or coloring. With such a combination the locations of a selected number of buttons, buttonholes, eyelets, etc., may be automatically marked. In the illustrated embodiment, the operation of the marking and feeding means is controlled by a starting and stopping mechanism arranged to rotate a driving shaft a selected number of revolutions or work cycles and to stop automatically the operation of the machine at the end of the selected number of cycles.

Another feature of the invention relates to novel mechanism constructed and arranged to mark uniformly buttonhole locations on the upper at a predetermined angle to the edge of the fly. As illustrated herein, a buttonhole marking element of the outline of a buttonhole is guided for marking operation so that it extends substantially at right angles to a fly edge guide against which the edge of the work is held during the marking operation.

A further feature of the invention consists in the combination with intermittently operated marking mechanism, of intermit-

tently operated work feeding mechanism constructed for reverse directions of feed. This feature is particularly advantageous in marking shoe uppers where right and left parts may be fed to the marking mechanism from opposite directions. The work feeding mechanism includes in addition, certain novel constructions for selectively varying the amount of the intermittent feeding movements.

In a step by step machine of the type involved in the present invention, when used for placing location marks at uniform distances from the edge of the stock, and especially stock having curved edges, it is important that the direction of feed of the stock to the marking instrumentality is such as to insure such uniform marking. Accordingly, a feature of the invention resides in a plurality of spaced gage members against which the edge of the stock is held and by which it is guided during the feeding operation to position properly the edge of the stock relatively to the marker. By having two contact points as guides the line of feed is fixed and accuracy is assured.

Another feature of my invention consists in the combination with an intermittently operated marking element of means for applying a coating of marking material to the marker prior to each marking operation. In the illustrated embodiment of the invention a reciprocating marking element is employed, and a color applying device is reciprocated transversely of the path of reciprocation of the marker to engage the marker and apply color thereto prior to marking movement of the element. These, and other features of the invention are more fully described in the following specification and are illustrated in the accompanying drawings, in which—

Figure 1 is a view in end elevation of a machine illustrating one embodiment of my invention, parts of the machine being shown in section to disclose interior mechanism;

Fig. 2 is a fragmentary perspective view of the stock marking and stock feeding mechanism;

Fig. 3 is a front elevation of the machine with parts broken away to disclose interior mechanism;

Fig. 4 is a view in side elevation and on an enlarged scale illustrating the positions of the parts for simultaneously marking the flies and quarters of folded uppers;

Fig. 5 is a fragmentary perspective view on an enlarged scale illustrating certain guiding, feeding and marking devices co-operating with a folded upper;

Fig. 6 is a detached perspective view of the two marking elements viewed from their under sides; and

Fig. 7 is a view of a folded shoe upper illustrating the relatively offset positions

of the buttonhole and button location marks, as applied to the folded upper by the method and machine of this invention.

The marking machine has a hollow base 2 with a hollow upstanding head 4 overhanging the base and having its front end closed by a removable face plate 6. A driven shaft 8 is journaled in this head and extends substantially parallel to a second driven shaft 10 journaled in the base 2. A bracket 12 extending rearwardly and downwardly from the head 4 supports one end of a driving shaft 14, the other end of which is mounted in the rear of the base 2, this shaft 15 being substantially parallel with the shaft 8 in the machine head. A driving pulley 16 is loosely mounted upon the outer end of the shaft 14 and is arranged to be continuously driven by suitable belting. Upon its 20 inner face the pulley is provided with a clutch socket 18 designed to receive and rotate a part projected from a member fastened to the driving shaft.

This member may take the form of a sleeve 20 fixed to the shaft 14 at the rear of the base and having an enlarged threaded collar 22 positioned on the shaft in juxtaposition to the inner face of the pulley 16. The threads of this sleeve enlargement will 30 be of predetermined pitch and number for coöperation with selective revolution governing mechanism, hereinafter described. The sleeve 20 and its enlargement 22 contain a longitudinal bore in which is mounted for 35 sliding movement a spring pressed locking pin 24 normally tending to move in a direction to enter into the socket 18 of the continuously rotating pulley 16. This pin 24 carries a transversely extending head 26 40 guiding in a slot formed in the sleeve 22 and extending longitudinally thereof.

The forward end of the shaft 14 carries a sprocket wheel 28 connected by a chain 30 with a similar sprocket wheel 32 mounted 45 upon the shaft 8 in the machine head to rotate said shaft at the same speed. Adjacent this sprocket the shaft carries an eccentric 34 with an arm 36 extending from the eccentric strap and pivotally connected to the 50 end of a crank arm 38 secured to the rear end of shaft 10 in the machine base. When the shaft 8 is rotated the shaft 10 is rocked or oscillated to operate certain stock feeding mechanism hereinafter described.

55 At its forward end the head 4 of the machine is enlarged and extends downwardly toward the base 2. The forward end of the shaft 8 extends within the upper end of this enlargement and has fixed thereto 60 a disk 40 formed with a peripheral cam groove 42. The outer face of this disk carries an eccentric pin 44 to which one end of a link 46 is pivotally connected, the other and upper end of the link being pivotally 65 connected to clamp member 48 holding and

reciprocating a plunger 50, whose upper and lower ends are guided in the upper and lower portions of the head 4 of the machine.

The lower end of the plunger 50 is hollow and contains a coiled spring 52 operating 70 against a plunger foot 54 guided for movement in a predetermined direction relative to the plunger 50 by means of a pin 56 in the plunger coöperating with a vertical slot 58 in the plunger foot. The plunger itself 75 is guided and prevented from turning by a pin 57 in the head 4 extending into a slot 59 in the upper end of the plunger. The lower end of the foot 54, as shown, is of substantially reduced diameter and has clamped 80 thereto a removable marker 60 whose marking base 62 may be shaped to correspond with the outline of the part to be cut out or worked. In the illustrated machine, the marking portion 62 is shown as outlining a 85 buttonhole, the projecting end of the foot 54 forming the eye, and is especially designed to mark buttonhole locations upon the flies of shoe uppers.

The markers 62 may be of any desired 90 type. For instance, in order to provide a mark which is clearly discernible upon all types of upper material, it is desirable to employ a marker which applies a colored mark to the stock. Accordingly, an arm 64 95 is pivoted to the machine head at 66 and has its upper end provided with a roller 68 which is guided in the cam groove 42 of the disk 40. The lower portion of the arm is offset, as at 70, and thence extends downwardly toward the bed 2 of the machine, as at 72 (Figs. 1 and 2). Its lower end is forked to embrace the pin 74 of a reciprocatory ink pad carrier 76 moving transversely of the line of reciprocation of the plunger 50 and 100 105 preferably guided by spaced edge guides 78 (Figs. 1 and 3) carried by spaced arms 79 depending from the head 4 and having longitudinal grooves 791 in their side faces into which the flanged edges of the carrier 76 110 extend. Through the cam 40, the arm 64 will be rocked to slide the ink pad carrier 76 to and fro on its edge guides in a direction transversely of the line of movement of the plunger carried marker 62. This operation is timed to occur when the plunger 50 has been moved to the upward limit of its stroke, so that the marker is inked prior to each marking movement.

At its base the downwardly projecting 120 portion of the forward end of the machine head is formed with a socket 80 in which is adjustably mounted a vertical rod 82. This rod extends down to a point adjacent the top of the machine bed and is provided 125 with an enlargement 84 (Fig. 5). Extending laterally from this enlargement and detachably secured thereto by the screw 86, is a combined stock edge gage and marker. This device may take the form of an elong- 130

gated member 88 having a relatively flat stock guiding face 90.

When the device is to be used for guiding the edges of stock of curved outline, such as 5 buttonhole flies, this face 90 will preferably be concaved to correspond substantially with the average curvature of buttonhole flies. The guide surface 90, when vertically positioned to coöperate with the work edge, is 10 spaced laterally a predetermined distance from the adjacent end of marker 62 so that the location marks will be uniformly spaced from the edge of the material. The marker 62 will extend at a determinate angle to the 15 longitudinal gaging line of surface 90, this angle being predetermined by the adjustment of the marking base 62 about the stem formed by the reduced lower end of the plunger foot 54, this plunger being held 20 against axial turning movement by the pin 56 and slot 58 and the marker being held in angularly adjusted position on the lower end of this plunger by a set screw as shown (Fig. 4).

25 At the face opposite the guiding surface 90, the member 88 is formed with a flat base 92 whose edge 94 forms a second stock edge guiding face which, when the parts are adjusted to the position shown in Fig. 4, is 30 positioned in a vertical plane to guide the edge of the buttonhole fly similarly to the guide surface 90 in Fig. 1. The lower edge of the vertically disposed guide face 94 is, however, elevated a greater distance above 35 the work supporting feed wheel than the corresponding edge of guide surface 90, so that the guide face 94 is elevated to a horizontal plane corresponding to the plane of the overlying buttonhole fly on the united 40 upper. Guide surface 90 is utilized, of course, for guiding the edges of buttonhole flies before they are stitched to the other parts of the upper. Secured to the under face of the plate 92 by a suitable clamping 45 screw, is a spring blade 96 whose outer end is bent upwardly (Fig. 6) and is positioned in the line of movement of the plunger actuated marker 62. The under face of the upwardly bent portion of the plate 96 carries a 50 prick point 98 positioned at a point slightly beyond the eye end 54 of the buttonhole marker in the direction of the edge of the buttonhole fly (see Fig. 4).

The length of the plunger stroke is such 55 as to apply sufficient pressure either directly or through intervening substance, to the spring blade 96 so as to straighten out the spring bend in the blade and to force said blade downwardly to cause this prick 60 point to mark the substance beneath the blade. When the plunger is raised, the spring of the bend in blade 96 will lift up the front end of the blade so that the material can be fed without interference by the 65 prick point 98. By one adjustment, there-

fore, the member 88 forms an edge guide for the stock edge in a single piece marking operation such as marking buttonhole flies, and by another adjustment presents a second and similar edge guide and a second marker 70 actuated by the first marker to mark underlying portions of folded materials between which it is positioned. In order to permit this adjustment of the member 88, the bed 2 of the machine is cupped out, as at 100, 75 Fig. 1.

The stock is intermittently fed toward the marking devices described alternately with the marking movements of the plunger 50 and for certain predetermined distances. 80 One desirable form of mechanism for effecting this result includes a feed wheel 102 loosely mounted upon the rock shaft 10 and having the outer portion of its periphery roughened to grip the stock. The wheel is 85 of sufficient breadth to extend beneath the marking devices to act as an anvil for the markers and to receive the pressure from certain presser devices operating upon the upper face of the stock and thereby effectively to grip and feed the stock. This feed wheel extends above the surface of the bed plate 2 sufficiently to insure contact with work placed upon the base.

At the outer face of the feed wheel are 90 complementary oppositely toothed annular ratchet surfaces preferably in the form of wheels 104, 106 for rotating the feed wheel in opposite directions. The shaft 10 extends beyond the feed wheel and ratchet wheels 100 and carries at a point beyond the ratchet wheels a double armed lever 108 to whose opposite ends are pivoted spring pressed driving dogs 110, 112 overlying and normally tending to engage the teeth of the 105 ratchet wheels 104, 106 respectively. The ends of the arms 108 carrying the driving dogs extend out through an annular slot 114 formed in the outer face of a ratchet-inclosing shield 116 of annular form.

This shield is carried by a sleeve 120 which, in turn, is fixed to a second inner sleeve 122 forming a housing for the reduced outer end of the rock shaft 10 and itself enlarged at its outer end to form an operating knob 124 with a laterally extending arm 126 positioned at the outer face of the base 2. Rotation of the knob 124 will, therefore, 115 rotate the ratchet shield 116.

The driving dogs 110, 112 are offset from 120 the extended ends of the arms 108 to overlie their respective ratchet wheels and normally tend to engage these ratchet wheels. The shield 116 covers the toothed peripheries of both ratchet wheels, except for those 125 portions of the ratchet wheels exposed between the spaced ends 118 (Fig. 2) of the shield, which ends are beveled downwardly toward the ratchet teeth so as to cause the ends of the driving dogs to ride up on the 130

shield when they are moved in the direction of the shield edge and into contact therewith. The range of movement of the dogs is fixed by the predetermined rocking movement of the shaft. As these dogs are in opposed relation only one driving dog may engage a ratchet wheel in any one operative position of the shield 116, as the opening in the shield extends for only a relatively short portion of the periphery of the shield and is designed to represent the maximum length of a single feeding movement of the feed wheel. Since the crank arm 38 swings both upwardly and downwardly with each revolution of driven shaft 10, the double armed lever 108 will swing equal distances in reverse directions during each revolution. Only one of the driving dogs 110, 112 can engage its ratchet through the shield opening during these two swinging movements of lever 108, the other driving dog riding idly over the closed peripheral portion of the shield.

By varying the position of the shield opening relatively to the field of movement of the operative driving dog, the effective length of the driving stroke of the dog may be varied at will. By reversing the position of the shield opening through the knob 124, the opposite and formerly inoperative driving dog is permitted to operate through the shield opening to rotate its oppositely toothed ratchet wheel and the feed wheel in the reverse direction for reversing the direction of feed of the stock, while the formerly active driving dog is guided up on to the outer peripheral face of the shield and rides idly over its closed peripheral face portion out of engagement with its ratchet wheel. The arm 126 of knob 124 affords means for holding the shield in different selected positions of feed control to vary determinately the direction of feed and the extent of feeding movement of the ratchets, so that the amount of stock fed between successive marking movements will be not only uniform as to one adjustment, but may be varied to suit the requirements of different cases.

Accordingly, the outer edge of the base 1 at points opposite the knob 124 is provided with segmental plates 128 having a series of apertures therein with adjacent descriptive data giving the length of feeding movement afforded by each adjustment. The end of the arm 126 carries a pivoted spring pressed latch 130 having a pin which normally tends to engage in the adjustment holes in the plates 128 to maintain the shield in the position selected for adjustment.

At the front of the machine head a presser head 132 is guided for reciprocating movement toward and from the feed roll 102 and is normally pressed toward the feed roll by a coiled spring 134 operating against the

head at one end and at the other end engaging an abutment 136 at the rear of the face plate 6. The face plate is slotted at 138 (Fig. 3) and a pin 140 attached to the presser head extends outwardly for engagement by the edge of a lifting lever 142 which is pivoted upon the outer face of the face plate 6. The spring 134 normally holds the pin 140 at the lower end of the slot and against the edge of the lever which is held by gravity in engagement with the pin. When the lever is pressed down to lift the presser head and its attached parts, the pin 140 will ride along the edge of the lever and snap into the notch 143 in its end, locking the lever and head against further movement and permitting the operator to use both hands in positioning the upper.

The head 132 at its lower end carries a conical presser roll 144 positioned directly above the roughened periphery of the feed wheel and co-operating with the feed wheel and with the work to feed that portion of the work inwardly of the presser wheel more rapidly than that portion of the work at the outer edge of the presser wheel, thereby imparting a turning or swinging movement to the work.

Depending from the opposite sides of the presser head are complementary spring presser arms 146 arranged to engage the upper face of the work at opposite sides and in line with the marker 62 to prevent wrinkling or puckering of the work when operated upon by the marker. These spring presser arms carry integral inward extensions 148 to which are adjustably secured combined stock edge guide arms and work end gages 150. The arms 150 are provided with curved flanges 152, forming stock edge guides co-operating with the central guide surfaces 90, and 94, the end of these flanges adjacent the marker constituting a visual end gage for initially positioning the end of the work relatively to the marker.

This construction is particularly advantageous when used in guiding the edge of buttonhole flies, either alone or as part of a folded shoe upper. One guide flange 152 will engage the edge of the buttonhole fly in co-operation with the central guide 90 or 94, while the inner end of the complementary flange 152 will act as a visual guide for positioning the end of the buttonhole fly a predetermined distance from the buttonhole marking point. The distance of the first buttonhole from the end of the buttonhole fly is the same for all shoes in a large proportion of factories but the practice in this respect is not uniform. In order to provide for variance in the first buttonhole position, the arms 150 are slotted and may be moved relatively to the end of the arms 146 and fixed in adjusted position by means of screws or other desirable clamping devices.

6
Preferably, as shown, the arms 148, 150 will bear suitable indication marks to facilitate accurate adjustment.

When the lever 142 is operated the presser wheel with the presser arms and edge gages will be lifted upwardly from the plane of the work to permit the insertion of the folded upper with the spring plate marker 96 inserted beneath the buttonhole fly. The lever 10 may then be released whereupon the presser head will be moved downwardly by its spring to engage the upper.

The construction described provides a machine which is particularly adapted for marking buttonhole flies and button quarters under widely varying conditions of manufacture. In some factories the button fly is marked for the buttonholes and these buttonholes are worked in the fly before the latter is stitched to the quarter and the upper folded. Subsequently, the quarter is marked for the buttons through the buttonholes in the superposed buttonhole fly. The machine of this invention is adapted by slight adjustment to accomplish both of these marking operations and is also adapted to mark both the buttonhole locations and the button locations substantially simultaneously upon the folded upper.

30 To mark the buttonhole fly alone, the work feeding mechanism is first adjusted to give the desired spacing between the marks and then the fly is inserted and its edge positioned against the guiding instrumentalities and relatively to the gaging means, as described. The machine is then started by operating a clutch, and through mechanism hereinafter described is operated through the number of work cycles corresponding 35 to the number of marking operations desired, and is then automatically stopped. The position of the parts for marking the buttonhole fly separately is indicated in Fig. 1.

45 When the fly has been operated upon to form the buttonholes and is then subsequently stitched to the quarters of the upper and the upper folded so that the parts are properly overlapped, it may be operated 50 upon by the same machine to mark the button locations on the quarter by adjusting the gage member 88 to the position indicated in Figs. 2, 4 and 5. The lever 142 is operated to lift the presser head with its 55 attached parts and the upper is inserted beneath the marking instrumentalities, the spring blade 96 entering between the button fly and the quarter, and the edge of the button fly resting against the edge guide 94 and the appropriate edge guide 152. The feed is adjusted to correspond with that by 60 means of which the buttonhole locations in the fly were originally marked, and the machine is started as heretofore described. The 65 buttonhole marker 62 is preferably detached

and the foot 54 will operate through the successive buttonholes to depress the spring blade 96 and mark the button locations on the button quarter, the spring blade 96 rising after each stroke to lift its prick point 70 clear of the quarter and permit the folded upper to be fed forwardly for the next marking operation.

When the fly and quarters have been united and folded without being first marked 75 for buttonholes and buttons the corresponding buttonhole and button locations may be marked on the fly and button quarter substantially simultaneously, by inserting the folded upper in the machine in the manner 80 just described, and operating the clutch, whereupon the marker 62 will automatically place the colored outline of the buttonhole upon the fly and will at the same time, by pressure transmitted to the spring blade 96 85 through the fly, cause the prick point of that blade to mark the button location on the underlying quarter at a point offset from the end of the buttonhole in the direction of length of the buttonhole. As the plunger 90 is lifted up the spring blade 96 will rise to lift its prick point clear of the quarter and permit the feeding movement of the upper for the next marking operation.

In all marking operations, the operator, 95 after initially positioning the work, is only required to press the button fly inwardly against the edge gages for the fly and to maintain it in engagement with these guiding means. The feeding mechanism and the 100 guiding means will maintain the proper direction of feed and the fly will be guided in the proper path of movement so long as its fly edge is maintained in engagement with these guiding surfaces.

105 The number of marking operations will vary with different sizes and styles of uppers or upper stock. A mechanism adapted to automatically operate the driving shaft to give a predetermined and selected number of marking movements to the mechanism will be a great desideratum. Accordingly, I have provided a mechanism arranged for adjustment to rotate the driving shaft 14 a selected or predetermined number 110 of revolutions and thereby to operate the driven shaft 8 and rock shaft 10 for a selected number of work cycles.

115 One embodiment of such a mechanism which may be advantageously used in this connection includes a vertically movable bar 154 bifurcated to partially embrace the sleeve 20 on the driving shaft 14, one arm of the bifurcation being provided with a cam face 156 terminating at its lower end 120 in a socket 158. The cam face is formed to engage the head 26 of the clutch pin to retract the pin from engagement with the continuously rotating pulley 16, the head of the pin being retracted and finally seating in 125 130

the socket 158 of this arm which acts as an abutment to stop further rotation of the sleeve 20.

The opposite arm 160 of the bar is extended upwardly above the sleeve 20 and into and through a socket 162 formed in the bracket 12 at the rear of the machine head. The upper portion of the bar is reduced in diameter to form a stem 164 which projects beyond and above the bracket 12 and carries an adjustable stop or abutment 166 at its upper end. Between this abutment and the face of the bracket 12 a coiled spring 168 is interposed, the tension of this spring normally tending to move the arm 160 and the bar 154 with the cam face 156 upwardly and into position to engage the cam face 156 with the head 26 of the clutch pin so as to move and hold the clutch pin in retracted position.

The bar 154 is pulled downwardly to clear the head 26 of the clutch pin and permit the latter to be thrown by its spring into clutching engagement with the driven pulley 16 by means of a rod 170 operated by a treadle or other suitable means (not shown). The rod 170 is guided in a bracket 172 at the base of the machine and is slotted at its upper end to house a pivoted trigger 174, the lower end of which is normally spring pressed outwardly to engage in a notch 176 formed in the edge of the bar 154 near its lower end. The upper end of the trigger is formed with a beveled face 178 which engages the edge of the bracket 172 after the bar 154 has been pulled down sufficiently far to release the clutch pin and permit the sleeves 20, 22 to be clutched to the rotating pulley 16.

When the bar has been depressed to this extent the beveled face of the trigger will engage the side of the bracket 172 and the lower end of the trigger will be thereby forced from engagement with the edge of the notch 176, releasing the bar 154 which under the influence of the spring 164 would normally tend to return into the plane of revolution of the head 26 of the clutch pin and would, under ordinary circumstances, coöperate with the pin head and retract the clutch pin at the end of one revolution of the driven shaft 14, the head of the clutch pin and the driven shaft being stopped when this head reaches the socket 158, the bar 154 and its spring 168 acting as a cushioning abutment. I have, however, provided means for preventing the automatic retraction of the clutch pin until the driven shaft has been operated for a definite and selected number of revolutions.

Accordingly, in the illustrated embodiment, the bar 160 at a point above the sleeve 20, has an offset 180 channeled in its upper face to provide a guideway 181 whose face is slightly curved. Sliding lengthwise in this

guideway is a latch-releasing bar 182 having its forward end slotted and guiding upon a pin in the lower portion of the head 4 of the machine frame which is provided with an opening at this point to receive the end 70 of the latch releasing bar. The arm 160 of the clutch-pin retracting arm 154 is formed with a socket 184 therein at a point above the bar 182 and with a slot 186 extending longitudinally of the arm and entering laterally upon the socket. Guided in this slot for vertical movement toward and from the latch-releasing bar 182 is a block 188 carrying an outwardly extending pin 189 arranged to engage the upper edge of the bar 80 182 and having spaced washers thereon embracing the opposite sides of the bar.

A spring pressed plug 190 is seated in the socket 184 and normally operates against the block 188 to hold the pin 189 pressed 85 against the bar 182. At one side of the arm 160 an abutment piece 192 is provided, this abutment coöperating with a latch block 194 carried by a spring pressed latching lever 196 pivoted to the bracket 12. When the 90 treadle rod 170 is operated to pull the bar 154 with its arm 160 downwardly to release the clutch pin the upper edge of the abutment piece 192 will be brought below the lower edge of the latching plate 194 which 95 will be immediately snapped over the upper edge of abutment piece 192 by its spring and will prevent the return of the bar 154 to clutch pin retracting position until the latching lever 196 is moved to the left to place its 100 latching block 194 out of the path of upward movement of the abutment 192.

In order to effect this release of the latching lever 196 to cause automatic retraction of the latch pin and the consequent stopping 105 of the driving shaft 14 at the end of the predetermined number of revolutions, the end of the latch-releasing bar 182 is provided with a downwardly extending tooth 198 arranged to engage in one of the threads 110 of the sleeve 22 when the bar 154 is pulled downwardly and latched. When this action takes place the tooth 198 will be held yieldingly against the threads of the rotating sleeve 22 by reason of the spring pressure 115 exerted against the bar 182 by the pin 189. During the rotation of the sleeve 22 the bar 182 will be fed by the threads of the sleeve toward the left (Fig. 1) until a pin 200 carried by the bar engages the lower end 120 of the lever 196 and moves its latch block 194 out of the path of upward movement of the abutment 192.

The pitch of the threads 22 and the position of the releasing pin 200 are in a definite ratio. For instance, if the tooth 198 were positioned to drop in the first thread at the left of the sleeve 22 (Fig. 1) and the bar 154 were pulled downwardly through the treadle and latched through the action 130

8
of the parts 192, 194, the pin 200 would be positioned against the edge of the latch lever 196 and one revolution of the threaded sleeve 22 would move the lever 96 a sufficient 5 distance to release the abutment 188, whereupon the spring 164 would move the bar 154 upwardly to bring its cam face 156 in the path of the head of the clutch pin, to retract the clutch pin at the end of the second revolution.
10

In order to secure a single revolution with the clutch pin automatically withdrawn at the end of the revolution, the heel of the lever 196 can be held upwardly by hand, 15 holding the latch block 194 out of the path of movement of the abutment 192, so that the ordinary one cycle action of the clutch will take place.

To position the tooth 198 for engagement 20 with different threads, a flange 202 or an equivalent bracket is provided at the rear of the machine head and is formed with a raised plate 204 having a series of location apertures 206 formed in the face of the 25 plate. A shifting lever 208 is pivoted between its ends on the horizontal portion of the bracket 12 and has its lower end bifurcated and in sliding engagement with a pin at the rear end of the unlatching bar 182. 30 The upper end of the lever 208 is flattened and formed as a finger 210 normally pressed toward the left (Fig. 1) by a spring pressed 35 plunger 212 mounted in the bracket 12 and bearing against the lever 208 at a point between its pivot and its upper end.

A gage pin 214 may be placed in any of the apertures 206 corresponding to the number of revolutions which it is desired the machine shall be operated and the lever 208 40 automatically swings its upper end to engage the gage pin 214 and at the same time, swings its lower end to position the tooth 198 over the thread groove in the sleeve 22 corresponding with the number of 45 revolutions indicated by the selected aperture 206. These apertures will mark the position which the finger 210 of the adjusting lever should bear to bring the tooth 198 immediately above the thread groove for the 50 number of revolutions indicated by the specific aperture. The number of revolutions may be varied to suit different conditions of the use of the machine, the pitch of the threads may be varied in specific cases and 55 other changes may be made to suit varying conditions of work. The specific construction of this selective revolution clutch controlling mechanism forms no part of the present invention but has been selected as a 60 representative type of control adapted particularly to a machine of the type involved in the present invention. With the described machine organization, the feed adjustment is first made; then the selective revolution clutch control adjusted and the 65

work positioned for the first marking operation. The treadle is operated to pull the treadle rod 170 downwardly, releasing the clutch pin and causing the shaft 14 to re-volve. At the initiation of the cycle of operations, the parts will be in the positions shown in Fig. 1 of the drawings with the operative feed dog 110, at the forward limit of its feeding stroke and the inking pad 76 in contact with marker 62. As soon as the 70 rotation of shaft 14 begins, the shaft 8 will be rotated through the connecting chain and sprockets. Thereupon the inking pad 76 will withdraw from the yieldingly pressed marker 62, and simultaneously, the operative 75 feed dog 110 will begin to slide to the rear for the initiation of a feeding stroke. After the pad 76 has cleared the marker 62, the plunger 50 with the marker will begin a downward work marking stroke which will 80 be completed when the feed dog reaches the end of its rearward movement. This point will mark the end of a half revolution of shaft 8. From this point in the cycle the marker 62 with its plunger will begin to move upwardly away from the work and the operative feed dog 110 will begin its 85 forward work feeding movement. At the end of the cycle or one revolution of shafts 8 and 14 the plunger 50 will reach the limit of its upward movement and the feed dog 110 will reach the limit of its forward work-feeding stroke. Just prior to the end of the revolution the cam path 90 42 will begin to swing the arm 64 to move the inking pad 76 outwardly to engage the marker 62 as the plunger reaches the end of its upward stroke so as to ink the marker for the next marking operation. The parts have now returned to the positions shown in Fig. 1. If the selective revolution clutch control has been adjusted for a plurality of marking operations, other cycles similar to the one just described will follow until the desired number of marking 105 operations have taken place. Just subsequent to the initiation of the last cycle or revolution of the shaft 8 (it being understood that shafts 14 and 8 rotate at the same speed) the bar 182 will release the latching lever 196 110 so that the bar 154 will be moved upwardly by the spring 168 to place its cam face in the path of the clutch pin head 26 to retract the clutch pin and stop the rotation of the 115 driven shaft 14 at the end of the last revolution.

From the foregoing description it will be evident that a machine such as described, is of special utility for marking shoe uppers, and particularly for marking button-hole and button locations upon the button-hole fly and button quarter of shoe uppers. By reason of guiding means maintaining the direction of feed of the stock, the location marks will be uniformly spaced from the 130

edge of the stock and by reason of the feed adjustment, these location marks will be uniformly spaced from each other for each adjustment of the feed and their spacing 5 may be uniformly varied, as desired.

Machines employing gangs of markers have been proposed for use in marking buttonhole and button locations, but in all machines of the gang type, the problem is very 10 much complicated by the wide variance of pattern curves and the necessity of providing mechanism, usually complicated and requiring time in its adjustment, for positioning the markers for the varying pattern 15 curves. With a machine such as I have described herein, curve variance need not be considered, as each of the successive location marks will be based upon a gage point having a determinate relation to the marking 20 point, so that with the edge of the work against the gage point, there is no necessity of providing for curve variance.

Furthermore, the machine may mark both 25 buttonhole and button locations simultaneously; or may mark the buttonhole locations in the buttonhole fly first; and then subsequently locations on the button quarter to which the finished fly has been subsequently stitched, thereby providing a machine which 30 is practically universal and is adapted to variance in factory practice.

By having a selective revolution or work cycle mechanism coupled with an automatic feed, the machine becomes substantially 35 more efficient by reason of the time saved from repeated treadlings and hand positioning of the work and is additionally advantageous as compared to the gang type of marking machine, in that there is no necessity 40 of continued adjustment for curved variance. Except where limited by the prior art or by the specific terms of the appended claims, the invention as recited in the claims, is to be construed as of use generally for 45 marking purposes. The nature of the marking instrumentalities may also be varied and the marking or location marking means as recited in the claims is intended to cover marking broadly and to include marking by 50 cutting, indenting, perforating, counterizing or color application. The specific structural embodiment disclosed, while preferable, is also susceptible of modification within the scope of the claims and the spirit of 55 the invention.

Having thus described my invention, what I claim as new and desire to secure by Letters Patent of the United States is:—

1. A buttonhole location marking machine 60 having, in combination, a buttonhole location marking member, power operated means organized intermittently to actuate said member to mark, and mechanism connected with said power operated means and operated in timed relation to said marking mem-

ber and effective to feed the upper stock toward said marking member intermittently and between successive marking operations.

2. A buttonhole location marking machine having, in combination, a buttonhole location marking member, power-operated means organized intermittently to actuate said member to mark, and mechanism connected with said power operated means and operated in timed relation to said marking member, 70 and effective to feed the upper stock to said marking member intermittently and between successive marking operations, said mechanism including means for reversing the direction of feed for right and left shoe 80 uppers.

3. A buttonhole location marking machine having, in combination, a buttonhole location marking member, stock feeding means in coöperative relation to said member, and power operated mechanism for intermittently actuating said member to mark and for operating said feeding means to feed stock to said marking member intermittently and between successive marking operations, 90 said mechanism being organized to actuate said marking member and feeding means for a selectively predetermined number of marking operations.

4. A buttonhole location marking machine 95 having, in combination, a reciprocating plunger, a buttonhole marker carried by the plunger, means for reciprocating the plunger, and means for feeding the stock to the marker between successive marking movements of the plunger.

5. A buttonhole location marking machine having, in combination, a reciprocating plunger, a buttonhole marker carried by the plunger, means for reciprocating the plunger and means for feeding the stock to the marker between successive marking movements of the plunger, and including means for reversing the direction of feed to accommodate right and left parts. 110

6. A buttonhole location marking machine having, in combination, a reciprocating plunger, a buttonhole marker carried thereby, means for reciprocating the plunger, means for feeding the stock a uniform distance between each marking movement of the plunger, with means for determinately varying the extent of the stock feeding movement. 115

7. A buttonhole location marking machine 120 having, in combination, a reciprocating plunger, a buttonhole marker carried thereby, means for reciprocating the plunger, means for advancing the stock a determinate distance between each marking movement of the plunger, and means for stopping the operation of said plunger and feeding means at the end of a selectively predetermined number of marking operations. 125

8. A buttonhole location marking machine 130

- 5 having, in combination, a reciprocating plunger, a buttonhole marker carried thereby, means for reciprocating the plunger, a feed wheel, means for intermittently rotating said wheel to feed the stock between successive marking operations, and stock presser means opposed to said wheel and yieldingly engaging the opposite face of the stock.

10 9. A buttonhole location marking machine having, in combination, a reciprocating plunger, a buttonhole marker carried thereby, means for reciprocating the plunger, means to engage and guide the edge of the 15 buttonhole fly a predetermined distance from said marker, stock feeding means, and mechanism for operating said feeding means to advance the stock intermittently between successive marking movements of the 20 plunger.

10 10. A buttonhole location marking machine having, in combination, a reciprocating plunger, a buttonhole marker carried thereby, means for reciprocating the plunger, 25 fly edge gaging means arranged to engage and guide the edge of the fly at a predetermined distance from the marker, a feed wheel, means for intermittently driving said wheel to feed the fly toward the marker between successive marking movements of the 30 plunger, and stock engaging and pressing means at the opposite face of the fly opposed to the feed wheel arranged to be moved to inoperative position.

35 11. A button and buttonhole location marking machine having, in combination, marking members constructed and arranged for substantially coincident movement to engage the buttonhole fly and button quarter, respectively, of a folded button shoe upper, power operated mechanism for intermittently moving said marking means to mark the shoe upper, and means for feeding a folded shoe upper to said marking means 40 in timed relation to said mechanism and intermittently and alternately with the marking operations.

45 12. A button and buttonhole location marking machine having, in combination, marking members constructed and arranged for substantially coincident movement, to engage the buttonhole fly and button quarter, respectively, of a folded button shoe upper, power operated mechanism for intermittently moving said marking means to mark the shoe upper, and means for feeding a folded shoe upper to said marking means intermittently between successive marking operations, and including manually controlled means for reversing the direction of feed to accommodate right and left uppers.

50 13. A button and buttonhole location marking machine having, in combination, marking members constructed and arranged for substantially coincident movement, to engage the buttonhole fly and button quarter, respectively, of a folded button shoe upper, power operated mechanism for intermittently moving said marking means to mark the shoe upper, and means for feeding a folded shoe upper to said marking means intermittently between successive marking operations, and for substantially coincident movement, to engage the buttonhole fly and button quarter, respectively, of a folded button shoe upper, power operated mechanism for intermittently moving said marking means to mark the shoe upper, and mechanism constructed 55 and arranged to feed a folded upper to said marking means in timed relation to the operation of said mechanism and intermittently and alternately with the marking operations and for a predetermined number of 60 marking operations.

65 14. A button and buttonhole location marking machine having, in combination, marking members constructed and arranged for substantially coincident movement, to engage the buttonhole fly and button quarter, respectively, of a folded button shoe upper, power operated mechanism for intermittently moving said marking means to mark the shoe upper, and mechanism constructed 70 and arranged to feed a folded upper to said marking means in timed relation to the operation of said mechanism and intermittently and alternately with the marking operations and for a predetermined number of 75 marking operations.

15 14. A button and buttonhole location marking machine having, in combination, marking members constructed and arranged for substantially coincident movement, to engage the buttonhole fly and button quarter, respectively, of a folded button shoe upper, power operated mechanism for intermittently moving said marking means to mark the shoe upper, and mechanism constructed 80 and arranged to feed a folded upper to said marking means in timed relation to the operation of said mechanism and intermittently and alternately with the marking operations and for a predetermined number of 85 marking operations.

20 15. A button and buttonhole location marking machine having, in combination, a button location marker arranged to be positioned between the fly and quarter of a supported folded shoe upper, a buttonhole 90 location marker positioned above the button location marker, mechanism for intermittently moving said buttonhole marker in a direction to mark the buttonhole fly and to coincidentally actuate the button marker, and mechanism constructed and arranged to feed the folded upper toward said markers intermittently between successive marking operations.

25 15. A button and buttonhole location marking machine having, in combination, a button location marker arranged to be positioned between the fly and quarter of a supported folded shoe upper, a buttonhole 100 location marker positioned above the button location marker, mechanism for intermittently moving said buttonhole marker in a direction to mark the buttonhole fly and to coincidentally actuate the button marker, and mechanism constructed and arranged to feed the folded upper toward said markers intermittently between successive marking operations.

30 16. A button and buttonhole location marking machine having, in combination, a buttonhole location marker and a coöperating button location marker having its marking point offset relatively to the end of the marking portion of the buttonhole marker, mechanism for actuating said markers to mark substantially simultaneously the buttonhole and corresponding button locations on the fly and button quarter of a folded upper at relatively offset points, and means for supporting the folded upper in marking position.

35 16. A button and buttonhole location marking machine having, in combination, a buttonhole location marker and a coöperating button location marker having its marking point offset relatively to the end of the marking portion of the buttonhole marker, mechanism for actuating said markers to mark substantially simultaneously the buttonhole and corresponding button locations on the fly and button quarter of a folded upper at relatively offset points, and means for supporting the folded upper in marking position.

40 17. A button and buttonhole location marking machine having, in combination, a buttonhole location marker and a coöperating button location marker having its marking point offset relatively to the marking portion of the buttonhole marker, power operating mechanism for intermittently actuating said markers to mark substantially 115

45 17. A button and buttonhole location marking machine having, in combination, a buttonhole location marker and a coöperating button location marker having its marking point offset relatively to the marking portion of the buttonhole marker, power operating mechanism for intermittently actuating said markers to mark substantially 120

50 17. A button and buttonhole location marking machine having, in combination, a buttonhole location marker and a coöperating button location marker having its marking point offset relatively to the marking portion of the buttonhole marker, power operating mechanism for intermittently actuating said markers to mark substantially 125

55 17. A button and buttonhole location marking machine having, in combination, a buttonhole location marker and a coöperating button location marker having its marking point offset relatively to the marking portion of the buttonhole marker, power operating mechanism for intermittently actuating said markers to mark substantially 130

multaneously the buttonhole and corresponding button locations on the fly and button quarter of a folded upper, and means for supporting the folded upper and for 5 guiding its edge to present it in proper relation to the markers.

18. A button and buttonhole location marking machine having, in combination, a support for a folded shoe upper, a buttonhole 10 location marker positioned above said support, a button location marker disposed below said buttonhole marker with its marking portion offset from the marking portion of the buttonhole marker in the direction of 15 the edge of the buttonhole fly and arranged to be positioned between the fly and quarter of a folded shoe upper, and mechanism arranged to be operated to actuate said markers substantially simultaneously.
20. 19. A button and buttonhole location marking machine having, in combination, a support for a folded shoe upper, a buttonhole location marker positioned above said support, a button location marker disposed 25 below said buttonhole marker with its marking portion offset from the marking portion of the button marker in the direction of the edge of the buttonhole fly and arranged to be positioned between the fly and quarter of 30 a folded shoe upper, power operated mechanism for intermittently actuating said markers substantially simultaneously to mark the locations of successive pairs of buttons and buttonholes, and mechanism constructed and 35 arranged to feed the folded upper relatively to said markers in timed relation to the operation of said power mechanism and intermittently and alternately with the marking operations.
40. 20. A button and buttonhole location marking machine having, in combination, a button location marker constructed to be positioned between the fly and quarter of a supported folded upper and arranged to 45 move toward and from the quarter, a reciprocating buttonhole location marker positioned to engage and mark the fly at a point above the button marker and to simultaneously move the button marker toward the 50 quarter to mark the corresponding button location thereon, means to reciprocate said buttonhole location marker and fly edge guiding means to engage and guide the fly edge at a predetermined distance from said buttonhole location marking point.

55. 21. A button and buttonhole location marking machine having, in combination, a reciprocating plunger, a buttonhole marker carried thereby, means to reciprocate the 60 plunger, means to position and guide the edge of the fly of a folded upper a predetermined distance from said marker, a button location marker positioned to extend beneath the guided fly edge to a point in line with and offset from the outer end of the buttonhole 65

location in the direction of length of the buttonhole, said button marker being supported and arranged for movement toward the button quarter by marking engagement of the buttonhole marker with the superposed fly, 70 and mechanism for feeding the folded upper toward said markers intermittently and alternately with marking movement of the plunger.

22. A button and buttonhole location 75 marking machine having, in combination, a reciprocating plunger, a buttonhole marker carried thereby, means to reciprocate the plunger, means to position and guide the edge of the fly of a folded upper a predetermined distance from said marker, a button location marker positioned to extend beneath the guided fly edge to a point in line with and offset from the outer end of the buttonhole location in the direction of length 80 of the buttonhole, said button marker being supported and arranged for button location marking movement by marking engagement of the buttonhole marker with the superposed fly, and mechanism for feeding the 85 folded upper toward said markers intermittently and alternately with marking movement of the plunger, including a selective revolution starting and stopping mechanism for continuing the marking and feeding 90 movements for a selected and predetermined 95 number of marking operations.

23. A buttonhole locating marking machine having, in combination, a support for the shoe upper, a positioning gage for the 100 edge of a folded upper upon said support, a plunger positioned above the overlying fly of a folded shoe upper positioned on said support and constructed and arranged for movement to engage said fly at the buttonhole location, a button location marker supported and positioned to extend between the fly and quarter of the supported folded upper in line with said plunger and with its marking portion offset longitudinally from 110 the end of the buttonhole location, and means for reciprocating the plunger.

24. A button location marking machine having, in combination, a button location marker, means to guide a folded upper toward said marker with said marker positioned between the fly and button quarter, power operated means for intermittently actuating said marker, and means for intermittently feeding the folded upper to said 115 marker between successive marking operations.

25. A button location marking machine having, in combination, a support for the shoe upper, a button location marker supported and positioned to extend between the button hole fly and button quarter of a supported folded shoe upper, gaging means to position and guide the edge of the buttonhole fly at a predetermined distance from 120 125 130

said marker, a reciprocating plunger positioned above the buttonhole fly to move toward the buttonhole fly in the line of said button location marker to move said marker 5 against the underlying button quarter and power operated mechanism for reciprocating said plunger.

26. A button location marking machine for operating upon folded uppers having 10 buttonholes in the flies thereof comprising in combination, a support for the shoe upper, a button location marking member supported and positioned to extend between the buttonhole fly and button quarter of a supported folded shoe upper, gaging means to position and guide the edge of the fly with the buttonholes therein overlying said button marking member, a reciprocating plunger positioned above the supported upper 15 and arranged to operate through the buttonholes of the fly to engage and move the button location marking member to mark the underlying quarter and means for reciprocating said plunger.

25. 27. A button location marking machine having, in combination, a support for the shoe upper, a button location marker, supported and positioned to extend between the buttonhole fly and button quarter of a supported folded shoe upper, gaging means to position and guide the edge of the buttonhole fly at a predetermined distance from said marker, a reciprocating plunger positioned to move toward the buttonhole fly 30 in the line of said button location marker to move said marker against the underlying button quarter, means to reciprocate said plunger, and feeding mechanism engaging the folded shoe upper and intermittently 35 operated in timed relation to movement of the plunger to feed the upper toward said marker alternately with marking movement of the plunger.

28. A button location marking machine 45 for operating upon folded uppers having buttonholes in the flies thereof comprising in combination, a support for the shoe upper, a button location marking member supported and positioned to extend between the 50 buttonhole fly and button quarter of a supported folded shoe upper, gaging means to position and guide the edge of the fly with the buttonholes therein overlying said button marking member, a reciprocating plunger positioned to operate through the 55 buttonholes of the fly to engage and move the button location marking member to mark the underlying quarter, the marking portion of said member being offset from the end of the buttonhole in the direction of 60 its length, power operated mechanism for reciprocating the plunger, and mechanism for intermittently feeding the folded upper toward said marking member and plunger 65 in timed relation to the movement of the

plunger and between successive marking movements of the plunger, said mechanism including means for determinately varying the amount of feeding movement of the upper to correspond with the spacing of the 70 buttonholes in the fly and means for reversing the direction of feeding movement to accommodate right and left uppers.

29. A button location marking machine having, in combination, a support for the 75 shoe upper, a button location marker supported and positioned to extend between the buttonhole fly and button quarter of a supported folded shoe upper, gaging means to position and guide the edge of the button- 80 hole fly at a predetermined distance from said marker, a reciprocating plunger positioned to move toward the buttonhole fly in the line of said button location marker to move said marker against the underlying 85 button quarter, means for reciprocating the plunger, and feeding mechanism engaging the folded shoe upper and intermittently operated in timed relation to movement of the plunger to feed the upper toward said 90 marker alternately with marking movement of the plunger, with means for effecting the marking and feeding movements for a selected and predetermined number of marking operations.

30. Mechanism for marking button locations on button shoe uppers comprising a support for button shoe uppers, a marker and a carrier therefor, with means for relatively moving the marker and the upper to 100 mark the button location on the button quarter at a point offset from the outer end of the corresponding buttonhole location in the direction of the length of the buttonhole.

31. Mechanism for marking button locations on button shoe uppers comprising a support for button shoe uppers, a marker and a carrier therefor, with means for moving the marker toward the supported upper to mark the button location on the button 110 quarter at a point offset a predetermined distance from the outer end of the corresponding buttonhole location.

32. Mechanism for marking button locations on button shoe uppers comprising a 115 support for shoe uppers, a marker, a carrier therefor, means for intermittently operating the carrier to mark the face of the button quarter of the supported shoe upper at a point offset from the eye end of the corresponding buttonhole location in the direction of length of the buttonhole, and means for intermittently feeding the shoe upper relative to the marker alternately with such marking operations.

33. Mechanism for marking button locations on a folded shoe upper in which the buttonholes have been formed, comprising a button location marking element and a carrier therefor, means to position the but- 130

tonhole fly of the folded upper relatively to the marking element to offset said element from the eye end of the buttonhole in the direction of the length of the buttonhole 5 and means for relatively moving the carrier and the folded upper to mark the button location on the button quarter.

34. Mechanism for marking button locations on folded uppers in which the buttonholes have been formed, comprising a button location marking element, a movable carrier therefor, means arranged to engage and guide the buttonhole fly relative to the carrier to offset said marking element from 10 the eye ends of the buttonholes in the direction of length of the buttonholes, means for intermittently moving the carrier to mark the button quarter, and means for intermittently feeding the folded upper toward the 15 marking means alternately with each marking operation.

35. Mechanism for marking button locations on button shoe uppers comprising a button location marking element, a movable carrier therefor, means to guide the button quarter to position said marking element offset relatively to and beyond the eye end of the corresponding buttonhole in the direction of length of the buttonhole, with 20 means to operate said carrier to mark the button quarter.

36. Mechanism for marking button locations on folded shoe uppers comprising a marking element, a movable carrier therefor, means to guide the edge of the buttonhole fly to position said marking element offset relatively to the eye end of the buttonhole in the direction of length of the buttonhole, mechanism to operate said carrier 25 to mark the button quarter and to feed the upper to the marker intermittently and alternately with marking movement of the carrier including manually adjustable means to operate the said mechanism for a selected 30 number of marking operations.

37. A machine for marking buttonhole and button locations on the buttonhole flies and button quarters of shoe uppers having, in combination, a buttonhole location marker, a button location marker, coöperating work guiding means, mechanism for actuating said markers to mark substantially simultaneously the button and buttonhole locations on a folded shoe upper, 50 said work guiding means being constructed and arranged for adjustment to coöperate with a separate buttonhole fly to position the fly for coöperation with the buttonhole marker and for further adjustment to coöperate with a folded upper to position it 55 relatively to the button marker to receive on the quarter of the folded upper having the said fly attached with the buttonholes formed therein, the button location markers 60 from said button markers.

38. A machine for marking buttonhole and button locations on the buttonhole flies and button quarters of shoe uppers having, in combination, a buttonhole location marker, a button location marker, power 70 operated mechanism for intermittently actuating said markers substantially simultaneously, said mechanism including a reciprocating plunger for actuating said markers, and stock positioning and guiding 75 means, said plunger, markers and guiding means being constructed for relative adjustment and arranged, in one position of adjustment, to coöperate with buttonhole flies to mark buttonhole locations on said flies, 80 and arranged, in another position of adjustment to coöperate with a folded shoe upper to mark the button locations on the underlying quarters of the folded upper having the previously marked flies attached 85 with the buttonholes formed therein.

39. A machine for marking buttonhole and button locations on the flies and button quarters of shoe uppers having, in combination, a support for shoe upper parts, a reciprocating plunger movable toward said support, means for reciprocating said plunger, a buttonhole marker carried at the end of said plunger, a combined fly edge guide and button location marker supported adjacent to the marking point of said buttonhole marker and provided with a plurality of work edge guides, means to adjust said combined guide and marker to present, in one position of adjustment, a guide for the edge of a separate buttonhole fly, and in another position of adjustment to present a different guide for the fly edge of a folded upper and a button location marker extending between the fly and button quarter in 100 the line of movement of said plunger, and mechanism to intermittently feed the upper parts predetermined distances toward said plunger alternately with marking movement of the plunger.

40. That improvement in methods of making button shoe uppers which consists in uniting the fly and quarters of a button shoe upper, folding them in properly overlapped relation, utilizing the buttonhole locations 115 on the overlying fly as guides and marking the underlying button quarter at points spaced from the eye ends of the buttonhole locations in the direction of the edge of the buttonhole fly to indicate the points for the 120 subsequent attachment of the buttons.

41. That improvement in methods of making button shoe uppers which consists in uniting the fly and quarters of a button shoe upper, folding them in properly overlapped relation, utilizing the eye ends of the buttonhole locations on the overlying fly as guides and marking the button locations 125 on the underlying button quarter at points uniformly offset from said eye ends longitu- 130

dinally of the buttonhole locations in the direction of the edge of the buttonhole fly to indicate the points for the subsequent attachment of the buttons and to allow for the 5 tipping of the button in its fastening.

42. That improvement in methods of making button shoe uppers which consists in making the buttonholes in the buttonhole fly, uniting the fly and quarters of the button 10 shoe upper, folding them in properly overlapped relation, utilizing the eye ends of the buttonholes in the overlying fly as guides and marking the button locations on the underlying button quarter at points spaced 15 from said eye ends longitudinally of the buttonholes in the direction of the edge of the buttonhole fly to allow for overlay or tipping of the buttons in their fastenings, and subsequently fastening the buttons to the 20 quarter at the points so marked.

43. That improvement in methods of making button shoe uppers which consists in making the buttonholes in the buttonhole fly, uniting the fly and quarters of the button 25 shoe upper, folding them in properly overlapped relation, utilizing the eye ends of the buttonholes in the overlying fly as guides for the spacing and locating of the button location marks and marking on the underlying quarter through said buttonholes a series of button location marks offset 30 longitudinally from the eye ends of their corresponding buttonholes in the direction of the edge of the buttonhole fly, and subsequently attaching the buttons to the quarter 35 at the locations so indicated.

44. A machine of the class described having, in combination, a marking member for shoe stock, power operated mechanism for 40 intermittently operating said member to mark the stock and for intermittently feeding the stock to the marking member between successive marking operations, and manually adjustable controlling means for 45 said mechanism operative to stop said mechanisms at the end of a selectively predetermined number of marking operations.

45. A machine of the class described having, in combination, a marking member for 50 shoe stock, power operated mechanism for intermittently operating said member to mark the stock and for intermittently feeding the stock to the marking member between successive marking operations, and 55 means to stop said mechanism at the end of a selectively predetermined number of successive work cycles, comprising a clutch device for controlling the work marking and feeding mechanism with manually adjustable means effective to operate the clutch to 60 render said mechanisms inoperative at the end of a selectively predetermined number of work cycles.

46. A machine of the class described, comprising, in combination, a reciprocating 65

marker for shoe stock, stock feeding means and power operated mechanism arranged to operate alternately said marker and said stock feeding means for a selectively predetermined number of successive marking operations. 70

47. A machine of the class described, comprising, in combination, a reciprocating marker for shoe stock, stock feeding means, and power operated mechanism arranged to 75 operate alternately said marker and said stock feeding means for a selected number of successive marking operations.

48. A machine of the class described having, in combination, a marker for shoe stock, 80 stock feeding means, power operated mechanism for intermittently actuating said marker to mark the stock and for intermittently actuating said feeding means to feed the stock between successive marking operations, said mechanism including an operating shaft, a power driven shaft, a clutch arranged for manual operation to connect said shafts to operate the marking and feeding mechanism, and controlling means arranged for manual adjustment operative to disconnect the clutch and to stop the rotation of said operating shaft at the end of the number of work cycles selectively predetermined by said adjustment. 85

49. A shoe upper marking machine having, in combination, a reciprocating marker, stock feeding means, and mechanism for reciprocating said marker and for intermittently actuating said feeding means between 100 successive marking operations, including means for reversing the direction of feed. 95

50. A machine of the class described having, in combination, a reciprocating marker, stock feeding means, and mechanism for reciprocating said marker and for intermittently actuating said feeding means between successive marking operations, including manually controlled means for reversing the direction of feeding movement. 105

51. A machine of the class described having, in combination, a reciprocating marker, stock feeding means, and mechanism for reciprocating said marker and for intermittently actuating said feeding means between successive marking operations including a rotatable shaft, work engaging and feeding means thereon, and reversible driving dog and ratchet mechanism in operative driving connection with said shaft. 110

52. A machine of the class described having, in combination, a reciprocating marker, stock feeding means, and mechanism for reciprocating said marker and for intermittently actuating said feeding means between 125 successive marking operations including a rotatable shaft, work engaging and feeding means thereon, and reversible driving dog and ratchet mechanism in operative driving connection with said shaft, with means ad- 130

justable to vary the amount of work feeding movement of the driving dog.

53. A machine of the class described having, in combination, a base, a marker reciprocating relatively to the base, means for reciprocating said marker, and mechanism for feeding stock toward the marker intermittently and alternately with the marking movements thereof, including a ratchet feed 10 wheel, a reciprocating driving dog co-operating with the ratchet wheel and a curved shield interposed between the dog and ratchet wheel and arranged for adjustment relative to said dog and ratchet to vary the 15 area of ratchet wheel exposed to driving movement of the dog.

54. A machine of the class described having, in combination, a base, a marker reciprocating relatively to the base, means for reciprocating the marker, and mechanism for feeding stock toward the marker intermittently and alternately with the marking movements thereof, including oppositely toothed annular ratchet surfaces, an annular 25 shield inclosing said ratchet surfaces and having a ratchet driving opening therein, oppositely disposed driving dogs positioned outside of said shield to engage reversely the toothed ratchet surfaces, means to oscillate 30 said driving dogs and means for adjusting the annular shield to expose a portion of one ratchet surface to the driving action of one dog and to shield the remaining ratchet surface from the action of the other driving 35 dog.

55. A machine of the class described having, in combination, a base, a marker reciprocating relatively to the base, means for reciprocating the marker and mechanism for feeding the stock toward the marker intermittently and alternately with the marking movements thereof, including a rock shaft, a feed wheel loosely mounted thereon and positioned to engage and feed stock placed on 45 said base, complemental reversely toothed annular ratchet surfaces carried by said feed wheel, a rotatable annular shield inclosing said ratchet surfaces and having an opening therein exposing complemental portions of 50 both ratchet surfaces, oppositely disposed driving dogs supported from and oscillated by said rock shaft and positioned upon the exterior of said shield to engage the respective ratchet surfaces when a dog and the 55 shield opening coincide in position, and means for adjusting the shield to vary the position of its opening relatively to the driving dogs.

56. A shoe upper marking machine, comprising, in combination, a reciprocating marker, means for reciprocating the marker, a coating applying member reciprocating transversely of the path of reciprocation of the marker to engage and apply a coating of 65 marking material to the marker, mechanism

for feeding stock to the marker and for moving said member to apply a coating to the marker intermittently and alternately with the marking operations and guiding means to engage the edge of the stock to position said edge a determinate distance from said marker. 70

57. A shoe upper marking machine having, in combination, an intermittently operated marking element, means for reciprocating said element, means for intermittently feeding stock to said marking element alternately with its marking operations, guiding means to engage the edge of the stock fed to said element to position said 80 edge a determinate distance from the marking element, and means for applying a coating of marking material to the marking element prior to each marking operation thereof. 85

58. A shoe upper marking machine having, in combination, a reciprocating marking element, means for reciprocating said element, means for intermittently feeding stock to said marking element alternately 90 with marking movement thereof, guiding means to engage the edge of the stock fed to said element to position said edge a determinate distance from the marking element, and a coating applying member arranged to reciprocate transversely of the path of reciprocation of the marking element, with means for reciprocating said member to engage and apply a coating of marking material to the marking element in timed relation to and prior to each marking movement of said element. 95

59. A buttonhole location marking machine having, in combination, a base, an element reciprocating relatively to said base, 105 guiding means to engage the edge of a buttonhole fly to position said edge a determinate distance from said element, a marking member carried by said element and outlining a buttonhole and having its longitudinal axis positioned and maintained at a predetermined angle to the guided edge of said fly, and means for reciprocating said element to operate the marking member. 110

60. A buttonhole location marking machine having, in combination, a base, a gage member arranged to guide the edge of a buttonhole fly on the base, an element reciprocating relative to the base and carrying a marking device shaped to mark the line of 115 the buttonhole and having its longitudinal axis positioned and maintained at a predetermined angle to the guided edge of the fly, and mechanism for reciprocating said element. 120

61. A buttonhole location marking machine having, in combination, a base, a gage member arranged to guide the edge of a buttonhole fly on the base, a plunger reciprocating relative to the base and carrying a 130

marking device outlining a buttonhole and having its longitudinal axis positioned and maintained substantially at right angles to the guided edge of said fly, means for applying a coating of marking material to said marking device prior to each marking operation and mechanism for reciprocating said plunger to mark the buttonhole fly.

62. A machine for marking shoe uppers having, in combination, a support for shoe uppers, a reciprocating element mounted for movement toward and from said support and having a marking device thereon, means for reciprocating said element, and work edge gaging and guiding means provided with a plurality of gage faces adjustably supported relative to the upper support and constructed and arranged in different positions of adjustment to present different gage faces to the edge of the upper.

63. A machine for marking shoe uppers having, in combination, a support for a shoe upper, a reciprocating element mounted for movement toward and from said support and having a marking device thereon, means for reciprocating said element, a member adjustably mounted adjacent to the marking point of said reciprocating element provided with a plurality of work edge guides constructed and arranged in one position of adjustment to provide a guide determinately positioning the edge of the work from the point of engagement therewith of said marking device, and arranged in another position of adjustment to provide a second determinately spacing edge guide and a second marking device extending into the path of reciprocation of the first mentioned marking device for actuation thereby.

64. An upper marking machine having, in combination, a stock support, a marking element movable toward said support to mark, means for intermittently actuating said element to mark, a guide member positioned adjacent the stock marking point of said element arranged to engage and determinately space the edge of the stock from said marking point, a coöperating guide member positioned at one side of said first guide member, said members having stock edge guiding surfaces positioned in determinate alinement to maintain the stock edge in determinate relation to the marking element as the stock is fed toward the marking element.

65. An upper marking machine having, in combination, a stock support, a reciprocating marking element movable toward said support to mark, means for reciprocating said element, feeding mechanism constructed and arranged to engage the work to feed it toward said marking element, a guide member positioned adjacent the stock marking point of said marking element arranged to engage and determinately space

the edge of the stock from said marking point, and coöperating guide members at opposite sides of said first guide member and in determinate alinement therewith to engage and guide the stock edge in determinate relation to the marking element.

66. An upper marking machine having, in combination, a base, a reciprocating marking element movable toward said base to mark, means for reciprocating said element, a work edge gage positioned adjacent to the marking point of said element and arranged to guide and determinately space the stock edge from said marking point, mechanism to feed the stock toward the marking element intermittently and alternately with the marking movements of said element including a feed wheel engaging the under face of the stock, an opposed presser wheel movable to engage the upper face of the stock having oppositely extending presser arms movable therewith to engage the stock and carrying stock edge guiding members co-operating with said first named stock edge guide member to determinately position and guide the stock edge relative to the marking point of said element.

67. An upper marking machine having, in combination, a base, a reciprocating marking element movable toward the base to mark, means for reciprocating said element, mechanism for feeding the stock toward the marking element intermittently and alternately with the marking movements of said element including a feed member engaging the under face of the stock, a head normally moved toward the base, a central presser member carried by the head and opposed to said feed member at the upper face of the stock, and complemental end presser members carried by the head and engaging the upper face of the stock at opposite sides of the marking point of the marking element, with means whereby said head may be operated to withdraw the presser members from engagement with the stock.

68. An upper marking machine having, in combination, a stock support, a reciprocating marking element movable toward said support to mark, means for reciprocating said element, a central edge gage for the stock, complemental edge gages adjacent to and at opposite sides of said first gage and arranged to guide and determinately space the edge of the stock from the marking point of said element, said gages being arranged in a line corresponding substantially with the line of the stock edge to be guided.

69. An upper marking machine having, in combination, a base, a reciprocating marking element movable toward the base to mark, means for reciprocating said element, mechanism constructed and arranged to feed the stock toward the marking element including a feed member engaging

the under face of the stock and presser means arranged to be moved into and out of engagement with the upper face of the stock, said presser means supporting a 5 guide member positioned at one side of the marking point of said element and arranged to engage and guide the edge of the stock relatively to the marking point, and a co-operating alined guide member positioned 10 adjacent to the marking point of said element and in the line of feed of the edge of the stock.

70. An upper marking machine having, in combination, a stock support, a reciprocating marking element movable toward the support to mark, means for reciprocating said element, a stock edge gage positioned adjacent to the marking point of said element arranged to guide and space 15 determinately the stock edge from said marking point, complemental and co-operating edge gages at opposite sides of said first gage and in determinate alinement therewith, one of said complemental edge 20 gages providing a stock end gage to initially position the end of the stock for one direction of feeding movement and the other of said complemental gages providing a similar stock end positioning gage in the 25 opposite direction of feeding movement of the stock.

71. An upper marking machine having, in combination, a stock support, a reciprocating marking element movable toward the 30 support to mark, means for reciprocating said element, a stock edge gage positioned adjacent to the marking point of said element arranged to guide and determinately space the stock edge from said marking point, complemental and co-operating edge gages at opposite sides of said first gage and in determinate alinement therewith, one of said complemental edge gages providing a stock end gage to initially position the 35 end of the stock for one direction of feeding movement and the other of said complemental gages forming a similar stock end positioning gage in the opposite direction of feeding movement of the stock, and 40 mechanism constructed and arranged to feed the stock toward the marking element intermittently between successive marking movements of the element including means for reversing the direction of feed.

55. 72. An upper marking machine having, in combination, a stock support, a reciprocating marking element movable toward the support to mark, means for reciprocating said element, a stock edge gage positioned 50 adjacent to the marking point of said element arranged to guide and space determinately the stock edge from the marking point, and complemental edge gages movable toward and from the support and ar- 60 ranged normally to contact with the sup-

ported stock, one of said complemental gages forming a stock end gage to initially and determinately position the stock relatively to the marking element for the first marking operation in one direction of feed 70 of the stock toward the marking element, and the other complemental gage forming a similar stock end gage in the opposite direction of stock feed.

73. An upper marking machine having, 75 in combination, a stock support, a reciprocating marking element movable toward the support to mark, means for reciprocating said element, a stock edge gage positioned adjacent to the marking point of said element arranged to guide and determinately space the stock edge from the marking point, and complemental edge gages movable toward and from the support and arranged to normally contact with the supported stock, one of said complemental gages forming a stock end gage to initially and determinately position the stock relatively to the marking element for the first marking operation in one direction of feed 80 of the stock toward the marking element, and the other complemental gage forming a similar stock end gage in the opposite direction of stock feed, and mechanism ar- 85 ranged to engage and feed the stock toward 90 the marking element intermittently and alternately with marking movement of the element, and including means for reversing the direction of stock feed.

74. A machine for operating upon shoe 100 uppers comprising, in combination, a work support, a reciprocating member for operating upon the face of the supported work, means for reciprocating said member, a work edge gage mounted to yield upwardly 105 to pressure of the work fed toward said reciprocating member, and means for intermittently feeding the work.

75. A machine for operating upon shoe 110 uppers comprising, in combination, a work support, a reciprocating member for operating upon the face of the supported work, means for reciprocating said member, a combined work edge gage and presser member mounted to yield upwardly to pressure 115 of work fed toward said reciprocating member, and means for intermittently feeding the work.

76. A machine for operating upon shoe 120 uppers comprising, in combination, a work support, a reciprocating member for operating upon the face of the supported work, means for reciprocating said member, a work edge gage adjacent to said reciprocating member, means for intermittently 125 feeding the work toward said member and a plurality of presser members for engaging the face of the supported work upwardly yieldably to pressure of the work, including a presser member adjacent to said recipro- 130

cating member and a second presser member spaced therefrom in the direction of feeding movement of the work.

77. A machine for operating upon shoe uppers comprising, in combination, a work support, a reciprocating member for operating upon the face of the supported work, means for reciprocating said member, a work edge gage adjacent to said reciprocating member, means for intermittently feeding the work toward said member, a plurality of presser members for yieldingly engaging the face of the work including a presser member adjacent to the reciprocating member and a second presser member spaced therefrom in the direction of feeding movement of the work, and means for bodily lifting said presser members to permit insertion of the work beneath said reciprocating member and in coöperative relation to the edge gage.

78. A machine for operating upon shoe uppers comprising, in combination, a work support, a reciprocating member for operating upon the face of the supported work, means for reciprocating said member, a work edge gage adjacent to said reciprocating member, means for intermittently feeding the work toward said member and a plurality of presser members for engaging the face of the supported work upwardly yieldable to pressure of the work, including a presser member adjacent to said recipro-

cating member and a second presser member spaced therefrom in the direction of feeding movement of the work, said second presser member having a second work edge gage spaced from the first edge gage and the reciprocating member in the direction of work feeding movement.

79. A machine for operating upon shoe uppers comprising, in combination, a work support, a reciprocating member for operating upon the face of the supported work, means for reciprocating said member, a work edge gage adjacent to said reciprocating member, means for intermittently feeding the work toward said member, a plurality of presser members for yieldingly engaging the face of the work including a presser member adjacent to the reciprocating member and a second presser member spaced therefrom in the direction of feeding movement of the work toward said reciprocating member, and means for bodily lifting said presser members to permit insertion of the work beneath said reciprocating member and in coöperative relation to the edge gage, said second presser member having attached thereto a second work edge gage spaced from the first edge gage in the direction of work feed toward said reciprocating member.

In testimony whereof I have signed my name to this specification.

HERBERT E. ENSLIN.

Copies of this patent may be obtained for five cents each, by addressing the "Commissioner of Patents, Washington, D. C."

It is hereby certified that in Letters Patent No. 1,313,943, granted August 26, 1919, upon the application of Herbert E. Enslin, of Malden, Massachusetts, for an improvement in "Methods of and Machines for Marking Shoe-Uppers," errors appear in the printed specification requiring correction as follows: Page 10, line 32, claim 10, strike out the word "opposite;" page 11, line 27, claim 19, for the word "button" read *buttonhole*; page 14, line 120, claim 51, for the word "connecting" read *connection*; and that the said Letters Patent should be read with these corrections therein that the same may conform to the record of the case in the Patent Office.

Signed and sealed this 23d day of December, A. D., 1919.

[SEAL.]

M. H. COULSTON,
Acting Commissioner of Patents.

Cl. 33—190.
